(57) CLAIM

The ornamental design for dietary supplement, as shown and described.

DESCRIPTION

FIG. 1 is a perspective view of the dietary supplement embodying the new design;

FIG. 2 is a front elevational view thereof;

FIG. 3 is a right side elevational view thereof;

FIG. 4 is a left side elevational view thereof;

FIG. 5 is a top elevational view thereof; and,

FIG. 6 is a bottom elevational view thereof.

FIGS. 1–6 show portions of the dietary supplement in broken lines. The portions shown in broken lines are shown for environmental purposes and do not form any part of the claimed design.
